UNITED STATES PATENT OFFICE.

JAMES POLK TODD, JOHN STEEL WELCH, AND LUCIAN MASON MCLENDON,
OF CHATFIELD, TEXAS.

BLASTING-CARTRIDGE.

SPECIFICATION forming part of Letters Patent No. 406,154, dated July 2, 1889.

Application filed July 14, 1888. Serial No. 279,931. (No model.)

To all whom it may concern:

Be it known that we, JAMES POLK TODD, JOHN STEEL WELCH, and LUCIAN MASON MCLENDON, citizens of the United States, residing at Chatfield, in the county of Navarro and State of Texas, have invented new and useful Improvements in Blasting-Cartridges, of which the following is a specification.

The invention relates to improvements in blasting-cartridges, the objects being to prevent the shell of the cartridge from flying out of the bore when exploded and to cause the cartridge to expand itself in a large degree laterally; and it consists in the construction and novel combination of parts hereinafter described, illustrated in the accompanying drawings, and pointed out in the appended claims.

In the drawings, Figure 1 is a perspective view of a blasting-cartridge embodying our invention. Fig. 2 is a face view of one of the sections of the cartridge. Fig. 3 is the cartridge in place in a recess or bore in a stump of a tree.

Referring to the drawings by letter, A designates a blasting-cartridge, preferably of malleable iron, and composed of two similar and equal longitudinal sections *a a*, each semicircular in cross-section, and together forming the cartridge-tube. The recess or hollow *a'* in the shell increases in diameter from its outer to its inner end, so that no shoulders that might produce irregular fracture when the shell is exploded are formed therein. This construction of the recess will also tend to force the front ends of the sections laterally outward, and consequently increase the disrupting force of the cartridge.

B is the tamp at the outer end of the cartridge, and *b* is the fuse-opening, the fuse extending centrally through said opening to the charge C within. The fuse *c* is of any desired construction.

D, Fig. 3, is a stump of a tree, into a bore *d* in which the cartridge is inserted. The outer or front end of each section *a* of the cartridge is provided with the teeth E on its outer surface, which teeth are arranged in parallel longitudinal rows *e*, the members of

each of which rows break joints with those of the adjacent rows. Each tooth E is wedge-shaped and has the oppositely-inclined sides *f*, the junction or ridge *f'* between which inclines inwardly and rearwardly.

F are shoulders at the front ends of the teeth, standing outward at right angles to the corresponding section.

From the described construction it is evident that when the cartridge is exploded the sections *a* will be separated and driven laterally and the teeth E will be embedded in the rock or wood that is disrupted, the shoulders *F* preventing the sections *a* of the cartridge from being blown outward by the explosion.

We are aware of the patent to Holsey, No. 140,628, dated July 8, 1873, and we disclaim the construction shown in said patent.

By making the adjacent faces of the semi-shells smooth and flat for their entire lengths, the said shells will easily separate when the blast takes place, and the fuse-opening will at no time become closed, which would give the shell a tendency to fly in an upward and outward direction, whereby much of the force of the blast, which should be entirely in a lateral direction, would be lost. Furthermore, by placing the exterior spurs or projections at the front end of the shell only, the cartridge may be withdrawn after being partially inserted in the drill hole or opening if a false start should be made in so inserting it, which could not well be done if the said teeth or spurs were extended over the entire length of the cartridge. At the same time they will be found amply sufficient for the purpose for which they are intended—viz., retaining the shell or cartridge in position in the opening prepared for its reception. The semi-shells composing our improved cartridge are not liable to become warped or misshapen by repeated use, inasmuch as they will readily part or separate when the blast takes place.

Having described our invention, we claim—

A blasting-cartridge composed of two similar semi-cylindrical sections having flat smooth faces their entire length, adapted to rest or bear against each other and grooved to form the cylindrical fuse-opening, and the

bore tapering from said fuse-opening to the bottom or inner end of the shell, said semi-shells being provided on their outer sides and at their front ends for a portion of their 5 lengths only with sharp-pointed spurs or projections having vertical front walls and sharp inclined rear edges, substantially as and for the purpose set forth.

In testimony that we claim the foregoing as

our own we have hereto affixed our signatures to in presence of two witnesses.

JAMES POLK TODD.
JOHN STEEL WELCH.
LUCIAN MASON McLENDON.
